ABSTRACT

A tube wall for a metallurgical furnace is mainly formed by an array of generally parallel tubes centered on respective tube axes and each having two widened open tube ends one of which projects laterally from the respective tube in one radial direction and the other of which projects laterally from the respective tube in the opposite radial direction. Each tube end laterally engages the tube end of an adjacent tube and the tubes are laterally spaced between their ends. Respective caps each cover two adjacent tube ends and interconnect same so that the interiors of the tubes and caps form a sinuous passage. Finally, respective welds secure the tube ends and caps together hermetically to seal off the passage. Thus appropriate means can circulate a coolant through the array. Such construction is sufficiently rigid to do away with webs laterally interconnecting the tube sections, thereby eliminating the cost of their manufacture and installation.

COOLED TUBE WALL FOR METALLURGICAL FURNACE

CROSS REFERENCE TO RELATED APPLICATION

This is a continuation of co-pending application Ser. No. 602,323 filed on Apr. 20, 1984, abandoned, which application is a continuation in part of Ser. No. 378,250 filed May 14, 1982, now U.S. Pat. No. 4,453,500.

FIELD OF THE INVENTION

The present invention relates to a metallurgical furnace. More particularly this invention concerns a cooled tube wall for an electric-arc furnace or the like.

BACKGROUND OF THE INVENTION

It is known to provide coolable tube walls for metallurgical vessels or furnaces that allow the lining to be kept relatively cool, that is as compared to the high refining or other treatment temperatures, and hence rigid. Such systems normally have a succession of laterally spaced straight tube sections joined at their ends by reverse bends or full 180° elbows, and joined laterally by rigid webs that form of the tube wall a rigid self-supporting structure. The bends have a radius of curvature which determines the spacing of the tubes, and the width of the webs. A cooler is connected to such an assembly to pass a coolant such as water or steam through it.

The fabrication of such a tube wall is an extremely complex procedure, involving meticulous interfitting of the various parts and then welding them together along seams that run the full length of each tube section, between it and the adjacent web plate and annularly around each tube end and the respective end of the reverse-bend coupling. Thus each tube has two annular welds connecting it to the respective reverse bends, and two full-longitudinal welds connecting it to the respective webs, with yet another semicircular weld extending as a continuation of the respective full-longitudinal weld between each web end and the inside of the respective reverse bend. Obviously all such welds must be carefully inspected, particularly where they cross, a location where the second weld is liable to weaken the first.

Even the most carefully made such structure is subjected to great stresses from thermal expansion and contraction, due principally to the difference in temperature between the interconnecting webs and the tubes themselves. The webs are, obviously, much warmer than the tubes, so that the welds between them and the tubes are under enormous strain. Since these welds are very long, it is possible for the stresses between the relatively hot tubes and relatively cool webs to be effective in turn along the entire tube length, placing the system under great strain.

In addition such systems are problematic because these long weld seams along the walls of the tubes slightly weaken these tubes in this region. Thus it is necessary to make the tubes of stock which is sufficiently thick to withstand the considerable pressures it will be subject to in use, even though such thickness is only needed at the weakened weld regions. In other words, if it were not for these webs it would be possible to make the tube sections of substantially lighter stock, rated purely for the pressure they will have to with-

stand, without allowing for the weakening caused by welding the webs to them.

OBJECTS OF THE INVENTION

5 It is therefore an object of the present invention to provide an improved tube wall.

Another object is the provision of such a tube wall which overcomes the above-given disadvantages.

10 A further object is to provide a tube-wall assembly for a metallurgical furnace, in particular an electric-arc furnace, which can be manufactured simply and cheaply, yet which will have a service life at least as long as the more difficult to manufacture prior-art ones.

15 It is also an object of the invention to extend the principles of our above-mentioned copending application.

SUMMARY OF THE INVENTION

These objects are attained according to the instant 20 invention in a tube wall for a metallurgical furnace which is mainly formed by an array of generally parallel and straight tubes centered on respective tube axes and each having two widened open tube ends one of which projects laterally from the respective tube in one radial direction and the other of which projects laterally from the respective tube in the opposite radial direction. Each tube end laterally engages the tube end of an adjacent tube and the tubes are laterally spaced between their ends. The tube ends are open axially, not radially 25 or laterally. Respective caps each cover two adjacent tube ends and interconnect same so that the interiors of the tubes and caps form a sinuous passage. Finally, respective welds secure the tube ends and caps together 30 hermetically to seal off the passage. Thus appropriate means can circulate a coolant through the array.

Such constructions is sufficiently rigid to do away with the webs, thereby eliminating the cost of their manufacture and installation. As a result production costs are greatly reduced. Furthermore thinner-walled 40 tube sections can be used, since the tubes are not welded between their ends with the concomitant wall weakening. Thus according to this invention the caps are of greater wall thickness than the tubes.

According to another feature of this invention the 45 array is received in a support wall provided with anchors engaging the tubes generally at the weld between the tube ends and wholly supporting the array.

Such a support wall may itself be formed of or have 50 a lining of refractory material suspended by the anchors from the support wall. In most cases the array is upright and the anchors are hooks engaged up underneath the upper caps.

The tube ends according to this invention are welded together for fluid flow between the tubes at the tube ends as well as at the caps. These caps in turn are rounded and form smooth continuations of the respective tube ends.

The tubes according to this invention are substantially cylindrically tubular between their widened ends. 60 The ends in turn can be oval so that they are tangent parallel to the respective axes. Thus the rounded outer faces of the tubes can be unwelded at their tangent line. Such a connection is extremely strong, as the welds include respective generally U-shaped welds lying in a plane parallel to the respective axes and extending along the tangent of the mutually engaging outer faces of the tubes. Even though there is a double wall thickness at the junction formed by each pair of joined faces, the

temperature here will be the same, as the wall forming each such face will have one side exposed to the temperature of the liquid in the passage and the other side against the corresponding side of the other wall which is similarly heated.

The vessel therefore has a normally metallic outer wall provided with inwardly projecting support hooks on which the tube-wall assembly and refractory lining is hung. The tube-wall itself purely serves a cooling function, does not hole in the melt, which task is adequately preformed by the combination of the refractory mold lining and the solid outer wall. The vessel lining or wall therefore carries the lining-support hooks, so that they do not have to be secured to the tubes or caps, an operation that would only weaken them. These hooks also serve to hold the tube-cap array in place.

Eliminating the webs also greatly reduces the thermally caused stresses in the tube wall. Since the tubes and caps are heated to the same extent and are usually of the same steel, they will swell and shrink as they are heated and cooled to the same extent. There are no cooler ribs that will be less thermally expanded.

DESCRIPTION OF THE DRAWING

The above and other features and advantages will become more readily apparent from the following, reference being made to the accompanying drawing in which:

FIG. 1 is a large-scale side view, partly broken away, showing the wall tube system of this invention;

FIGS. 2 and 3 are sections taken along lines II—II and III—III of FIG. 1, respectively;

FIG. 4 is a small-scale side view showing the assembly of this invention installed; and

FIG. 5 is a section taken along line V—V of FIG. 4.

SPECIFIC DESCRIPTION

As seen in the drawing a cooled tube wall has a multiplicity of like tubes 1 centered on respective upright parallel axes A and formed with enlarged ends 4 joined together by coupling caps 2. The enlarged ends 4 are welded to the caps 2 along a planar and annular seam 3 and to each other along a U-shaped seam 6 perpendicular thereto but parallel to the respective axis A. To this end each of the widened ends 4 is of oval section and has a rounded face 12 parallel to the respective axis A and engaging the respective face 12 of the respective end 4 of the adjacent tube 1 along a tangent, so that the tubes 1 bear against each other and are solidly connected together by seams 6 extending along their line of contact and perpendicular to the plane of seam 3 stress urging them apart. The seam 6 has a U-shape and extending along the tangent on opposite sides thereof and below the tangent.

The enlarged ends 4 project from opposite sides of the respective tube sections 1 to form between each tube section 1 and the adjacent tube sections 1 gaps 5 having centerlines 7 parallel to the tube axes A. This type of construction, with open spaces between the tubes 1, allows the self-supporting assembly formed by the sections 1 and caps 2 to be suspended from conventional anchor hooks 9 of a furnace wall or furnace-lining

wall 8 shown in FIGS. 4 and 5. Otherwise these hooks 9 serve to hold on the furnace lining or slag shown only partially at 11 in FIG. 5.

A cooler 10 including a pump circulates water or steam through the meander formed by the sections 1 and caps 2 in a manner well known in the art. The caps 2 have a wall thickness d (FIG. 1) which is somewhat greater than the wall thickness d' (FIG. 3) of the tube sections 1 and end portions 4 so that the arrangement is very rugged. The caps 2 are indented at 2' so that oval tubular portions thereof at 2a and 2b register with the enlarged ends 4 of the tubes 1 bridged thereby.

We claim:

1. A tube wall for a metallurgical furnace said wall comprising:

an array of generally parallel cylindrical tubes centered on respective tube axes and each having two widened axially open tube ends of oval cross section one of which projects laterally from the respective tube in one radial direction and the other of which projects laterally from the respective tube in the opposite radial direction, each oval tube end laterally engaging the oppositely projecting oval tube end of an adjacent tube along a common tangent, said adjacent tubes being laterally spaced between their engaging ends;

respective caps each covering two adjacent tube ends and interconnecting same, whereby the interiors of said tubes and caps form a sinuous passage, said caps being indented and having oval tubular portions registering with the oval cross section tube ends covered thereby, said adjacent tubes being laterally spaced between their engaging ends;

respective caps each covering two adjacent tube ends and interconnecting same, whereby the interiors of said tubes and caps form a sinuous passage, said caps being indented and having oval tubular portions registering with the oval cross section tube ends covered thereby, said welds including a U-shaped weld seam extending along opposite sides of each tangent to weld the laterally engaging tube ends together and a peripheral planar weld extending between the periphery of each cap and the respective tube ends, the U-shaped weld of each cap being perpendicular to the planar weld thereof; and

means for circulating a coolant through said array, said caps being rounded and forming smooth continuations of the respective tube ends, said caps being of greater wall thickness than said tubes, said array being upright and received in a support wall provided with anchors engaging said tubes generally at the welds between said tube ends and wholly supporting said array, said anchors being hooks engaged up underneath the upper caps; and a lining of refractory material suspended by said anchors from said support wall.

2. The metallurgical-furnace tube wall defined in claim 1 wherein said caps are rounded and form smooth continuations of the respective tube ends.
